ADJUSTABLE CHAISE

Albert P. Krikorian, Agawam, Mass.

Application November 3, 1952, Serial No. 22,108

Term of patent 7 years

(Cl. D15—11)

To all whom it may concern:

Be it known that, I, Albert P. Krikorian, a citizen of the United States, residing at Agawam, in the county of Hampden and Commonwealth of Massachusetts, have invented a new, original, and ornamental Design for an Adjustable Chaise, of which the following is a specification, reference being had to the accompanying drawing, forming part hereof.

The single figure is a side perspective view of an adjustable chaise showing my new design.

The characteristic features of the chair reside in the arm members and their unique relation to and association with the combined back and seat and foot portions of the chair and the base portion of the chair.

I claim:
The ornamental design for an adjustable chaise, as shown and described.

ALBERT P. KRIKORIAN.
